UNITED STATES PATENT OFFICE.

WILLIAM C. LANG, OF EAST CLEVELAND, OHIO.

HOT-AIR FURNACE.

Application filed November 18, 1925. Serial No. 69,797.

This invention relates to improvements in hot-air furnaces and pertains to a furnace more especially comprising a combustion-dome mounted on a fire-pot and also two vertically spaced heat-radiating drums surrounding and spaced from said dome.

One object of this invention is to so construct and relatively arrange said dome and said drums that an exceedingly high efficiency in the utilization of the products of combustion in the furnace is attainable.

Another object is to so form, relatively arranged and connect together said drums and said dome that the lower drum is rigid with the dome, that said lower drum has an interior passageway extending circumferentially of the space between said drum and the dome and placed in communication, at one end portion thereof, with the dome, and that the upper drum is arranged over and supported from the lower drum and has an interior passageway extending circumferentially of the space between the upper drum and the dome and placed in communication, at one end portion thereof, with the other end portion of the passageway in the lower drum and having an outlet arranged as required to render it capable of participating in conducting products of combustion to a chimney from the other end portion of the passageway in the upper drum.

Another object is to cause the products of combustion entering the interior passageways of said drums to pass with facility in one and the same direction in said passageways circumferentially of the combustion-dome.

Another object is to render said dome and said drums, and the connection between the dome and the lower drum, simple and durable in construction and highly practical.

Another object is not only to attain an improved circulation of the products of combustion in the furnace but to provide improved and highly practical means whereby products of combustion may be conducted laterally from the lower portion of the combustion-dome to the hereinbefore mentioned chimney without passing into the hereinbefore mentioned passageway in the upper drum.

Another object is to form said dome and the lower dome-surrounding drum of a single iron casting comprising a flue which extends between said lower drum and the lower portion of the dome and constitutes the in-

let of said drum and the outlet of the dome, and to provide said lower drum, at its outer side, with a laterally and outwardly projecting flue-forming tubular member arranged substantially in line with said outlet of the dome and constituting a portion of a hereinafter described valved passageway adapted to be placed in communication with the hereinbefore mentioned chimney.

With these objects in view, and to attain other objects hereinafter appearing, this invention consists in certain meritorious features of construction, and combinations and relative arrangements of parts, hereinafter described in this specification, pointed out in the claims, and illustrated in the accompanying drawings.

In said drawings, Figure 1 is a central vertical section of a portion of a hot-air furnace embodying my invention. Fig. 2 is a section, in detail, taken along line 2—2 in Fig. 1 and is drawn on a larger scale than Fig. 1. Fig. 3 is a central vertical section taken along line 3—3 in Fig. 1. Fig. 4 is a horizontal section taken along line 4—4 in Fig. 1. Fig. 5 is a vertical section, in detail, taken along line 5—5 in Fig. 4. Fig. 6 is a horizontal section, in detail, taken along line 6—6 in Fig. 1. Fig. 7 is a vertical section, in detail, taken along the curved line 7—7 in Fig. 4.

Figs. 1, 3, 4 and 6 of said drawings show the upper portion of the fire-pot 10 of my improved furnace. Said furnace comprises a combustion-dome 12 mounted on the upper end of and communicating with the fire-pot 10, and the joint formed between said dome and the fire-pot may be rendered fluid-tight in any approved manner.

An air-chamber 13 is formed next externally of and surrounds the fire-pot 10 and combustion-dome 12 and extends above said dome, and 15 indicates an upright cylindrical casing forming a surrounding wall of said chamber and extending above said dome. The chamber 13 has a top wall 16 which has upwardly projecting spaced flue-forming tubular members 17 communicating with the constituting outlets of said chamber. Air may be supplied to the chamber 13 in any approved manner, and heated air ascending in said chamber is adapted to be conducted in any approved manner from the outlets 17 of the chamber to the rooms or space to be heated. Obviously the casing 15 and top wall 16 would not be used in a fur-

nace installed on the floor of a room or space to be heated.

My improved furnace comprises an annular heat-radiating drum 18 arranged substantially concentrically in relation to the combustion-dome 12 and extending around the lower portion of and spaced from the dome. Said drum 18 has an interior passageway 19 extending circumferentially of the space between the drum and the dome 12, and a flue 20 communicates, at its inner end, with the dome and constitutes a lateral outlet of said dome. Said flue 20 communicates, at its outer end, with the passageway 19 and constitutes a lateral inlet of said passageway. The dome 12, drum 18, and flue 20 are preferably composed of cast iron and cast integral. The drum 18 has a substantially vertical interior transverse partition 21 which, as shown in Figs. 1 and 6, is arranged at one side of the outer end of the flue 20, and said flue establishes direct communication between the passageway 19 and the lower portion of the dome 12 only at one side of said partition. It will be observed, therefore, that one end portion of the passageway 19 is arranged wholly at one side of the partition 21 and communicates, at said side of said partition, with the flue 20, and said passageway extends from its inlet formed by said flue circumferentially of the dome 12 in the direction in which said side of said partition faces, and the other end portion of said passageway is arranged wholly at the opposite side of said partition. The drum 18 (see Figs. 3, 5 and 7) has a short upwardly projecting tubular member 23 formed at the top of the last-mentioned end portion of and communicating with the passageway 19 and constituting a top outlet of said passageway. The drum 18 is provided, at the outer side of said first-mentioned end portion of the passageway 19, with a laterally and outwardly projecting flue-forming tubular member 24 integral with said drum and preferably arranged opposite the outer end of and substantially in line endwise with the flue 20. The tubular member 24 of the drum 18 is in communication with the passageway 19 and therefore with the dome 12 and extends through the adjacent portion and externally of the casing 15 and may be used as a substantially direct outlet for products of combustion passing from said dome through the flue 20 into said passageway 19. The drum 18 is provided, at the top thereof (see Figs. 3 and 4), with upwardly projecting spaced lugs 25, and said drum (see Figs. 1 and 2) is provided, at its outer side, with laterally and outwardly projecting tubular members 26 which flare toward their inner ends and are integral with said drum and communicate with the passageway 19. The tubular members 26 extend through the adjacent

portion and externally of the casing 15 and afford convenient access to the passageway 19 for cleaning the walls of said passageway and are provided, at their outer ends, with clean-out doors 27.

My improved furnace (see Figs. 1, 3 and 4) also comprises an annular heat-radiating drum 28 arranged over and spaced upwardly from the lower drum 18 and supported from said lower drum as will hereinafter appear. The upper drum 28 extends around the upper portion of and is spaced from and substantially concentric in relation to the combustion-dome 12 and has an interior passageway 29 which extends circumferentially of the space between the dome and said upper drum. One end portion of said passageway 29 (see Fig. 7) extends over the top outlet 23 of the passageway 19 in the lower drum 18, and the upper drum 28 has an opening 30 formed at the bottom of said end portion and constituting the inlet of the passageway 29 in said upper drum and registering and communicating with said top outlet 23 of the passageway 19 in the lower drum 18.

As already hereinbefore indicated, one side of the interior partition 21 of the lower drum 18 faces in the direction in which the passageway 19 in said drum extends circumferentially of the space between said drum and the dome 12 from the inlet of said passageway, and I would here remark that the passageway 29 in the upper drum 28 (see Figs. 4 and 7) extends circumferentially of the space between said upper drum and the dome in said direction from over the outlet 23 of the lower drum 18. The upper drum 28 (see Figs. 3 and 4) is provided, at the outer side of the discharging end portion of the passageway 29, with a laterally and outwardly projecting flue-forming tubular member 31 which communicates with and constitutes a lateral outlet of said passageway 29 and extends substantially horizontally from said upper drum 28 through the adjacent portion and externally of the casing 15. The upper drum 28 (see Figs. 4 and 7) has a substantially vertical interior transverse partition 33 arranged between the inlet 30 of the passageway 29 and the outlet member 31 of said drum.

As shown in Figs. 5 and 7, the upper drum 28 has support on the outlet-member 23 of the lower drum 18, and the joint formed between said drums at said outlet-member 23 may be rendered fluid-tight in any approved manner. The upper drum 28 is seated on each lug 25 of the lower drum 18, and (see Figs. 3 and 4) preferably provided, at its bottom and at one side of each lug 25, with a foot-forming member 34 resting on said lower drum.

A substantially horizontal pipe 35 (see figs. 3 and 4) is attached at one end to and communicates with the outlet-member 31 of

the upper drum 28, and said pipe is provided, at its outer end, with a normally closed door 36 applied in any approved manner, and obviously when said door is opened 5 access is had through said pipe and member 31 to the adjacent portion of the passageway 29 in said drum for cleaning purposes. The pipe 35 is provided, at the top thereof between the outer end of the pipe and the 10 outer end of the outlet-member 31 of the upper drum 28, with an upwardly projecting tubular member 37 at which said pipe may be placed in communication with a chimney in any approved manner, and said pipe is 15 provided, at its side which is nearer the tubular member 24 of the lower drum 18, with a laterally projecting member 38 which forms a lateral outlet of said pipe and embraces one end of a curved pipe 40 arranged externally and extending circumferentially of the casing 15 to said member 38 of the pipe 35 from an elbow 41 which (see 20 Figs. 1 and 4) establishes communication between the pipe 40 and the vertical end 25 portion of an elbow 42 extending and establishing communication between the upper elbow 41 and the tubular member 24 of the lower drum 18.

The lower elbow 42 is provided interiorly 30 with a valve 43 preferably consisting of an upright plate which is arranged to be swung internally of said elbow and mounted at its lower end on and secured in any approved manner to a substantially horizontal shaft 35 44 supported from and extending externally of said elbow. The valve 43 is shown in its closed position in Figs. 1 and 2, and the shaft 44 is provided, externally of the elbow 42, with a crank 45 for rotating the shaft. 40 The valve 43 rests, when it is in its closed position, against a flange 46 formed on and internally of the elbow 42 and is obviously adapted to be actuated into an open position by the required manipulation of the 45 crank 45.

It will be observed that the tubular member 24 of the lower drum 18, the pipe 40 and the elbows 41 and 42 are adapted to be employed in forming a passageway arranged 50 to substantially directly receive products of combustion discharged through the flue 20 from the combustion-dome 12, and that the valve 43 controls communication through said passageway. It will also be observed 55 that the products of combustion discharged by the flue 20 into the passageway 19 in the lower drum 18, when the valve 43 is closed, passes endwise of said passageway 19 and only circumferentially of the space between said drum and the dome 12 in one 60 direction to and through the top outlet-member 23 of said drum into the passageway 29 in the upper drum 28 and endwise of the last-mentioned passageway in said 65 direction circumferentially of the space be-

tween said upper drum and the dome to and through the lateral outlet-member 31 of said upper drum into the pipe 35 from which products of combustion may be conducted, at the top-outlet 37 of said pipe, to a chimney 70 in any approved manner.

The upper drum 28 (see Figs. 1 and 4) is shown provided, at its outer side, with laterally and outwardly projecting tubular members 48 which flare toward their inner 75 ends and are integral with and spaced circumferentially of the drum and communicate with the passageway 29. The tubular members 48 extend through the adjacent portion and externally of the casing 15 and afford convenient access to and for cleaning the walls of the passageway 29 and are provided, at their outer ends, with clean-out doors 49. For convenience in internally 80 cleaning the drums 18 and 28 the tubular member 48 of each upper drum 28 (see Fig. 1) is preferably arranged over a tubular member 26 of the lower drum 18.

By the hereinbefore described construction and relative arrangement of parts an 90 adequate air-heating efficiency is insured and, during the operation of the furnace when the valve 43 is closed, the products of combustion pass with facility in the passageways 19 and 29 in one and the same direction circumferentially of the dome 12, and a remarkably high efficiency in the utilization 95 of the products of combustion is attained.

It will be observed that the combustion-dome 12 is non-partitioned so as to avoid a circuitous passage of products of combustion from the fire-pot through said dome to the flue 20, and not unimportant for attaining maximum heating efficiency is 105 the extension of said dome a considerable distance above the lower dome-surrounding heating drum into which the flue 20 discharges so that there is always an adequate 110 supply of hot gases internally of the upper portion of said dome and above the path of the products of combustion from the fire-pot to said flue during the operation of the furnace. Also, the bottom of the lower heating drum 18 is substantially flush with 115 the bottom of the flue 20 to facilitate the manufacture of said flue and said drum and dome 12 of a single casting. Also, the flue 20 is arranged wholly between the lower extremity of the dome 12 and a point central 120 between the upper and lower extremities of the dome, and the lower drum 18 extends around the lower portion of the dome and has its top substantially flush with the top 125 of said flue, so as to insure an adequate extension of said dome above said flue. Also, it will be observed that the short upwardly projecting tubular member 23 of the lower drum 18 serves not only as a top outlet for the passageway 19 in said drum but also 130

as a support for the upper drum 28, that the lugs 25 on the lower drum and the feet-forming members 34 of the upper drum serve in supporting the upper drum from the lower drum independently of the upwardly projecting tubular member 23 of the lower drum and also serve in adequately spacing said drums vertically, that the formation of the upper drum and its feet-forming members 34 and tubular projecting members 31 and 48, of a single casting, and the formation of the dome 12, the flue 20, and the lower drum and its tubular projecting members 23, 24 and 26 of a single casting facilities the assemblage of the component parts of the furnace, that the participation of the tubular member 24 of the lower drum in the formation of the herein-before described valved passageway and the arrangement of said member 24 at the outer side or circumference of said drum and substantially in line endwise with the flue 20 facilitates the passage of products of combustion from said flue into said valved passageway when, in starting a fire, said passageway is employed in conducting products of combustion to the chimney, and that the relative arrangement of the heating drums and aforesaid valved passageway substantially wholly above the lower extremity of the dome 12 are of vast importance for convenience in the assemblage of the parts and for maintaining the parts in repairs and in a clean condition.

35 What I claim is:—

1. A furnace comprising a fire-pot, a combustion-dome mounted on and communicating with the fire-pot, two vertically spaced heat-radiating drums extending circumferentially of and spaced from said dome, the lower drum being supported from the dome and having an interior passageway which at one end portion thereof has a lateral inlet communicating with said dome and extends circumferentially of the space between the dome and said lower drum and also has a top outlet at its other end portion, and a valved controlled passageway extending from the first-mentioned end portion of the first-mentioned passageway and adapted to be employed in conducting products of combustion from the furnace, the upper drum being supported from the lower drum and having an interior passageway which is in communication at the bottom of one end portion thereof with the aforesaid top outlet of the first-mentioned passageway and extends circumferentially of the space between said upper drum and the dome and has an outlet at its other end portion for conducting products of combustion from the furnace.

2. A furnace comprising a fire-pot, a combustion-dome arranged above and communicating with and supported from the fire-

pot, a flue extending outwardly from and communicating and rigid with the dome, two vertically spaced heating drums extending around and spaced from the dome, an air-chamber formed next externally of the drums and fire-pot and having outlets for hot air, and a valved passageway placed in communication with the aforesaid flue and adapted to be placed in communication with a chimney, the lower drum being rigid with said flue and having an interior passageway which communicates at the outer end of and with said flue and extends from said flue circumferentially of the dome to a point at which products of combustion are adapted to be discharged from said passageway and has a top outlet at said point, the upper drum being supported from the lower drum and having an interior passageway which communicates with said outlet and extends from said outlet circumferentially of the dome to a point at which products of combustion are adapted to be conducted from said passageway to the aforesaid chimney, and all of the aforesaid passageways being arranged substantially wholly above the lower extremity of the dome.

3. A furnace comprising a fire-pot, a combustion-dome arranged above and supported from and communicating with the fire-pot, a flue extending outwardly from and communicating and integral with the dome, two heating drums arranged the one above the other and each extending around and spaced from the dome, an air-chamber formed next externally of the drums and fire-pot and having outlets for hot air, and a valved passageway placed in communication with the aforesaid flue and adapted to be placed in communication with a chimney, the lower drum being integral with said flue and having an interior passageway which communicates at the outer end of and with said flue and extends from said flue circumferentially of the dome to a point at which products of combustion are adapted to be discharged from said passageway and has an outlet at said point, the upper drum being supported from the lower drum and having an interior passageway which communicates with said outlet and extends from said outlet circumferentially of the dome to a point at which products of combustion are adapted to be conducted from said passageway, and the bottom of the lower drum being substantially flush with the bottom of the aforesaid flue.

4. A furnace comprising a fire-pot, a combustion-dome mounted on and communicating with the fire-pot, a flue extending outwardly from and communicating and rigid with the dome, two vertically spaced heating drums extending around and spaced from the dome, an air-chamber formed next

externally of the drums and fire-pot and having outlets for hot air, and a valved passageway placed in communication with the aforesaid flue and adapted to be placed in communication with a chimney, the lower drum being rigid with said flue and having an interior passageway which communicates at the outer end of and with said flue and extends from said flue circumferentially of the dome to a point at which products of combustion are adapted to be discharged from said passageway and has an outlet at said point, and the upper drum being supported from the lower drum and having an interior passageway which communicates with said outlet and extends from said outlet circumferentially of the dome to a point at which products of combustion are adapted to be conducted from said passageway to a chimney, and a valved passageway adapted to be employed in conducting products of combustion from the passageway in the lower drum to said chimney and partially formed by a tubular member which extends externally of the aforesaid chamber from said drum and is integral with said drum and substantially in line endwise and in communication with the aforesaid flue.

5. A furnace comprising a fire-pot, a combustion-dome mounted on and communicating with the fire-pot, a flue extending outwardly from and communicating and rigid with the dome, two vertically spaced heating drums extending around the dome, an air-chamber formed next externally of the drums and fire-pot and having outlets for hot air, and a valved passageway placed in communication with the aforesaid flue and adapted to be placed in communication with a chimney, the lower drum being rigid with said flue and having an interior passageway which communicates at the outer end of and with said flue and extends from said flue circumferentially of the dome to a point at which products of combustion are adapted to be discharged from said passageway and has an outlet at said point, and a valved passageway adapted to be placed in communication with a chimney, the upper drum being supported from the lower drum and having an interior passageway which communicates with the aforesaid outlet and extends from said outlet circumferentially of the dome to a point at which products of combustion are adapted to be conducted to the aforesaid chimney, and the aforesaid valved passageway communicating at a point opposite the outlet end of the aforesaid flue, with the passageway in the lower drum and extending from said passageway in the lower drum to the exterior of the aforesaid chamber.

6. A furnace comprising a fire-pot, a combustion-dome mounted on and communicating with the fire-pot, a flue extending outwardly from and communicating and rigid with the dome, two vertically spaced heating drums extending around the dome, an air-chamber formed next externally of the drums and fire-pot and having outlets for hot air, the lower drum being rigid with said flue and having an interior passageway which communicates at the outer end of and with said flue and extends from said flue circumferentially of the dome to a point at which products of combustion are adapted to be discharged from said passageway and having outlets for hot air, the lower drum being rigid with said flue and having an interior passageway which communicates with the aforesaid outlet and extends from said outlet circumferentially of the dome to a point at which products of combustion are adapted to be conducted to the aforesaid chimney, and the aforesaid valved passageway communicating at a point opposite the outlet end of the aforesaid flue, with the passageway in the lower drum and extending from said passageway in the lower drum to the exterior of the aforesaid chamber.

7. A furnace comprising a fire-pot, a combustion-dome mounted on and communicating with the fire-pot, a flue extending outwardly from and communicating and rigid with the dome, two vertically spaced heating drums extending around the dome, an air-chamber formed next externally of the drums and fire-pot and having outlets for hot air, and a valved passageway placed in communication with the aforesaid flue and adapted to be placed in communication with a chimney, the lower drum being rigid with said flue and having an interior passageway which communicates at the outer end of and with said flue and extends from said flue circumferentially of the dome to a point at which products of combustion are adapted to be discharged from said passageway and has an outlet at said point, and the upper drum being supported from the lower drum and having an interior passageway which communicates with said outlet and extends from said outlet circumferentially of the dome to a point at which products of combustion are adapted to be conducted from said passageway to a chimney, and a valved passageway adapted to be employed in conducting products of combustion from the passageway in the lower drum to said chimney and partially formed by a tubular member which extends externally of the aforesaid chamber from said drum and is integral with said drum and substantially in line endwise and in communication with the aforesaid flue.

7. A furnace comprising a fire-pot, a combustion-dome mounted on and communicating with the fire-pot, a flue extending outwardly from and communicating and rigid with the dome, two vertically spaced heating drums extending around the dome, an air-chamber formed next externally of the drums and fire-pot and having outlets for hot air, and a valved passageway placed in communication with the aforesaid flue and adapted to be placed in communication with a chimney, the lower drum being rigid with said flue and having an interior passageway which communicates at the outer end of and with said flue and extends from said flue circumferentially of the dome to a point at which products of combustion are adapted to be discharged from said passageway, said lower drum being provided at said point with a short upwardly projecting tubular member which constitutes an outlet for the last-mentioned passageway and affords support to the upper drum, and the upper drum having support on the lower drum independently of said tubular projecting member and also having an interior passageway which communicates with said tubular projecting member and extends circumferentially of the dome from said projecting member to a point at which products of combustion are adapted to be conducted to the aforesaid chimney.

8. A furnace comprising a fire-pot, a combustion-dome mounted on and communicating with the firepot, a flue extending outwardly from and communicating and rigid with the dome, two vertically spaced heating drums extending around the dome, an air-chamber formed next externally of the drums and fire-pot and having outlets for hot air, and a valved passageway placed in communication with the aforesaid flue and adapted to be placed in communication with a chimney, the lower drum being rigid with said flue and having an interior passageway which communicates at the outer end of and with said flue and extends from said flue circumferentially of the dome to a point at which products of combustion are adapted to be discharged from said passageway and has an outlet at said point, and the upper drum being supported from the lower drum and having an interior passageway which communicates with said outlet and extends from said outlet circumferentially of the dome to a point at which products of combustion are adapted to be conducted from said passageway to a chimney, and a valved passageway adapted to be employed in conducting products of combustion from the passageway in the lower drum to said chimney and partially formed by a tubular member which extends externally of the aforesaid chamber from said drum and is integral with said drum and substantially in line endwise and in communication with the aforesaid flue.

a chimney, the lower drum being rigid with said flue and having upwardly projecting spaced lugs and an interior passageway which communicates with said flue at the outer end of the flue and extends from said flue circumferentially of the dome to a point at which products of combustion are adapted to be discharged from said passageway, said lower drum being provided at 10 said point with an upwardly projecting tubular member constituting an outlet for said passageway, the upper drum being seated on the aforesaid lugs and having an interior passageway which communicates with 15 said tubular projecting member and extends circumferentially of the dome from said projecting member to a point at which products of combustion are adapted to be conducted to the aforesaid chimney, and said 20 upper drum being provided, at one side of each of said lugs, with a foot-forming member resting on the lower drum.

9. A furnace comprising a fire-pot, a combustion-dome mounted on and communicating 25 with the fire-pot, a laterally extending flue communicating and rigid with the dome, two vertically spaced heating drums arranged substantially wholly above the lower extremity of and extending around and 30 spaced from the dome, an air-chamber formed next externally of the drums and fire-pot and having outlets for hot air, and a valved passageway largely arranged externally of said chamber and adapted to be 35 placed in communication with a chimney, the lower drum being rigid with the aforesaid flue and having an interior transverse partition and an interior passageway which extends circumferentially of the dome, one 40 end portion of said passageway in the lower drum being arranged at one side of said partition and communicating with the aforesaid valved passageway and with the aforesaid flue, the other end portion of the passageway in the lower drum being arranged 45 at the opposite side of said partition, said

lower drum being provided at the last-mentioned end portion of said passageway in the lower drum with a tubular projection constituting an outlet for said passageway, and the upper drum being mounted on the lower drum and having an interior passageway which communicates with said outlet and extends circumferentially of the dome from 50 said outlet to a point at which products of combustion are adapted to be conducted to the aforesaid chimney.

10. A furnace comprising a fire-pot, a combustion-dome mounted on and communicating with the fire-pot, a flue extending laterally outwardly from the lower portion of and communicating and rigid with the dome, two vertically spaced heating drums extending circumferentially of and spaced from the dome, an air-chamber formed next externally of the drums and fire-pot and having outlets for hot air, and a valved passageway placed in communication with the aforesaid flue and adapted to be placed in communication with a chimney, the lower 60 drum being rigid with said flue and having an interior passageway which communicates at the outer end of and with said flue and extends from said flue circumferentially of the lower portion of the dome to a point at 65 which products of combustion are adapted to be discharged from said passageway and has a top outlet at said point, the upper drum being supported from the lower drum and having an interior passageway which 70 communicates at the bottom thereof with said outlet and extends from said outlet circumferentially of the dome to a point at which products of combustion are adapted to be conducted from said passageway, and the dome being non-partitioned and extending a considerable distance above the lower 75 drum.

In testimony whereof, I sign the foregoing specification.

WILLIAM C. LANG.
